PORTABLE CHART RACK

Hyman Robert Shampaine, Clayton, Mo.

Application December 2, 1948, Serial No. 63,024

4 Claims. (Cl. 312—319)

1

This invention relates in general to chart racks, and, more particularly, to certain new and useful improvements in portable chart racks.

The primary object of the present invention is to provide a chart rack for use in a hospital and the like which is mobile and can be locked when not in use to prevent unauthorized removal of charts.

A further object of the present invention is to provide a portable chart rack having novel locking means which is simple and compact in construction and will not accidentally catch the fingers or otherwise injure the operator as it is being locked and unlocked.

An additional object of the present invention is to provide a movable chart rack which is simple and economical in construction and durable in use.

And with the above and other objects in view, my invention resides in the novel features of form, construction, arrangement, and combination of parts presently described and pointed out in the claims.

In the accompanying drawings (two sheets)—

Figure 1 is a perspective view of a chart rack constructed in accordance with and embodying the present invention;

Figure 2 is a side elevational view of the chart rack;

Figure 3 is a front elevational view;

Figures 4 and 5 are fragmental transverse sectional views taken along lines 4—4 and 5—5, respectively, of Figure 2;

Figures 6 and 7 are fragmental transverse sectional views taken along lines 6—6 and 7—7, respectively, of Figure 1;

Figure 8 is a fragmental transverse sectional view taken along line 8—8 of Figure 3;

Figure 9 is a fragmentary transverse sectional view taken along line 9—9 of Figure 5; and

Figure 10 is a fragmentary cut-away perspective view illustrating the locking bar in unlocked position.

Referring now by reference characters to the drawings, which illustrate a preferred embodiment of my invention, A designates a chart rack comprising a bottom wall 1, side walls 2, 2', having obliquely extending top margins m, and front and back walls 3, 4. The front wall 3 is relatively short and its top margin is coincidental with the lower end of the top margins m of the walls 2, 2', whereas the rear wall 4 has its top margin coincidental with the upper end of the top margin of the walls 2, 2', in the formation of an open topped housing or shell s the top open-

2

ing o of which is inclined upwardly and rearwardly from the forward wall 3 at an angle of approximately 45° for convenient access. Secured, as by screws, to the inner face of the walls 3, 4, adjacent their top margins are horizontally extending reinforcing angles 6, 7, having face flanges 6', 7', respectively, disposed in the plane of the top opening o. The front wall 3 is further provided centrally and adjacent its lower margins with a rectangular drawer opening 5.

Suitably secured to the underside of the bottom wall 1 adjacent the ends of the wall 2 are non-swiveling casters 8 and adjacent the ends of the rear wall 4 are swiveling casters 9. Maintained in outwardly spaced relation to the lower margins of the rack A by means of a plurality of short brackets 10 is an annular guard rail 11 provided on its outwardly presented surfaces with rubber cushioning strips x, as may best be seen in Figure 3.

Secured around its margins to the inner faces of the walls 2, 2', 3, 4, and extending horizontally therebetween in upwardly spaced relation to the bottom wall 1 is a false bottom member 12 in the provision of a compartment 13 into which the aperture 5 of the wall 3 opens and, similarly secured at their end to and extending horizontally between the front and rear walls 3, 4, on opposite sides of the opening 5, are conventional drawer slides 14 having ball bearing rollers 15 for operatively supporting laterally projecting slide flanges 16 welded or otherwise suitably secured upon the side walls 17 of a utility drawer 18 adapted to move in and out of the opening 5 and being provided with a coincidental handle 19 and lock 20.

Above the false bottom 12 and beneath the opening o is a holding space 21 preferably divided into three equal parallel sections a, b, c, by two wide or double sided chart supporting bars 22, 23, each mounted at their ends on and extending between the reinforcing angles 6, 7, parallel to the plane of the opening o. Also mounted at their ends on and extending between the angles 6, 7, adjacent the upper margins of each of the walls 2, 2', are narrow or single-sided chart supporting bars 24, 25, each parallel to the bars 22, 23. The bars 22, 23, 24, 25, are provided with a plurality of spaced sets of horizontally aligned U-shaped recesses 26 extending downwardly from their upper faces for receiving the roller-studs 27, 28, projecting axially from each end of conventional hospital charts 29, as best seen in Figure 1.

Formed integrally upon the upper faces of the bars 22, 23, 24, 25, adjacent the upper and lower

ends, respectively thereof, are flat faced bearing pads 30, 30', provided with vertically extending slots 31, 31', opening in vertical alignment with the aperture 30 radially downwardly into horizontal bores 32, 32', extending transversely through the bars 22, 23, 24, 25.

Extending horizontally through the upper bores 32 of each of the bars 22, 23, 24, 25, is a shaft 33 having primed thereon six spool-like collars 34, 35, 36, 37, 38, 39, each externally sized for snug-fitting rotation disposition within the bores 32 and being so positioned along the shaft 33 that the collars 34, 39, are located within the bore 32 of the narrow bars 24, 25, respectively, and the collars 35, 36, and 37, 38, are arranged in axially spaced pairs to fit respectively within the bores 32 of the wide bars 22, 23, with their outwardly presented or exposed faces substantially flush with the outwardly presented or lateral faces of the bars 22, 23. The shaft 33 is held against endwise translation by set collars 40 which bear against the inwardly presented lateral face of the narrow bars 24, 25, as shown in Figure 5.

Similarly extending through the lower bores 32' is a shaft 33' having primed thereon spool-like collars 34', 35', 36', 37', 38', 39', identical respectively to the collars 34, 35, 36, 37, 38, 39, in shape, size, and location to the shaft 33'. The shaft 33' is likewise held against longitudinal translation by set collars 40' which bear against the lateral faces of the narrow bars 24, 25.

Each of the collars 34, 34', 36, 36', 38, 38', are provided in their outer or peripheral faces with a so-called "right handed" spiral groove *g* and similarly the collars 35, 35', 37, 37', 39, 39', are provided with identical but opposite or "left handed" spiral grooves *g'* for actuating engagement with pins 41 extending downwardly through the slots 31, 31', and being rigidly mounted in the under faces of locking bars 42 which are, in turn, slidably disposed at their ends on the upper faces of the bearing pads 30, 30'.

At its rearward end the shaft 33' is turned down as at 43 for slidably fitting within the recess 44 axially bored in the inner end of a handle 45 mounted in and extending through the side wall 2'. Internally the handle 45 is provided with a conventional bored type lock 46 having an axially shiftable locking tongue 47 for operative engagement with a diametral slot 48 formed in the end 44 of the shaft 33'.

The doublesided or wide bar 22 is provided in its under face with a lengthwise extending milled slot 49 for slidably receiving a transmission bar 50 supported therein by pins 51 and provided on its ends with upwardly presented toothed or rack-forming sections 52, 52', which enter into the space between the pairs of collars 35, 36, and 35', 36', respectively, for engagement with spur gears 53, 53', which are in turn respectively pinned to the shafts 33, 33'. Thus, when the lock 46 is turned to engage the tongue 47 in the slot 48 operatively locking the handle 45 to the shaft 33', rotative movement of the handle 45 and shaft 33' will be simultaneously transmitted to the shaft 33, as best seen in Figure 8. The locking bars 42 extend lengthwise across the U-shaped recesses 26 and are adapted to shift laterally responsive to rotative movement of the handle 45. The locking bars 42 are in effect paired for movement toward and away from each other, that is to say, the bar 42 which is actuated by the collars 34, 34', and the bar 42 which is actuated by the collars 35, 35', will move toward each other when the shafts 33, 33', are rotated

in one direction, and away from each other when the shafts 33, 33', are rotated in the opposite direction. The locking bar 42 actuated by the collars 36, 36', is similarly paired with the locking bar 42 actuated by the collars 37, 37', and the locking bar 42 actuated by the collars 38, 38', is similarly paired with the locking bar 42 actuated by the collars 39, 39'.

Secured at their upper and lower ends by means of screws 54, 55, to the flanges 6', 7', respectively, of the angles 6, 7, and extending in upwardly spaced longitudinal relation thereto, are cover plates 56 which are slightly greater in width than the distance between the inner or adjacent margins of the locking bars 42 mounted thereunder when the latter are in extended or locked position (as shown in dotted lines in Figure 6) so as to close and conceal the working gap between said locking bars 42 and at the same time not interfere with chart removal when the locking bars 42 are in retracted position (as shown in full lines in Figure 6). Similarly mounted between the side walls 2, 2', and the chart holding bars 24, 25, adjacent thereto, are sheet metal angles or side covering members 57 the top flanges 58, of which, extend inwardly in upwardly spaced relation along the bars 24, 25, for concealing the working gap behind the locking bars 42 associated therewith, as best seen in Figure 7.

Mounted on the outer face of the wall 2' at a convenient height are spaced brackets 59 for supporting the ends of a push rod handle 60 extending therebetween for facilitating movement of the chart rack A by an operator. Hingedly mounted on the upper central portion of the back wall 4 is a desk forming utility shelf 61 optionally supported in horizontal position by a pair of spaced triangular-shaped brackets 62 which are vertically hinged upon the face of the back wall 4 beneath the shelf 61 and are adapted to be folded inwardly toward each other to lie flatwise against the face of the back wall 4 in concealed or nested position behind the shelf 61 when the latter is in vertical or in operative position, as shown in dotted lines in Figure 2.

In use the charts 29 are placed within the sections *a*, *b*, *c*, of the rack A with the ears 28 seated in an aligned pair of recesses 26 whereby the chart 29 depends within the space 21, as shown in Figure 1. Ordinarily the charts 29 may be fully removed from the rack A for inspection by authorized individuals. However, when it is desirable to lock the charts B in the rack A so that unauthorized persons will be denied access, the handle 45 is suitably rotated to shift the locking bars 42 from retracted position (as shown in full lines in Figures 6 and 7) to outwardly extended position (as shown in dotted lines in Figures 6 and 7) in which position they extend over the recesses 26 and block upward or withdrawing movement of the charts 29.

The rack A may be freely moved about, as from room to room in a hospital or from bed to bed in a large ward thereof and will provide both a complete and portable "office" so to speak, for the nurse or attendant in charge. For example, the utility drawer 18 may be utilized as a depository for thermometers, tongue depressors, stethoscopes, pen, ink, spare chart-forms and the like. The shelf 61 provides a writing surface whereby entries may be made in the charts 29 as the rack A is moved from location to location when the round of the patients has been completed the chart rack A may be locked until it is again

needed for the next round, thereby preventing ambulatory patients, visitors and other unauthorized persons from gaining access to the charts.

It will be understood that, while my invention has been described with reference to a preferred embodiment thereof, changes in the form, construction, arrangement, and combination of the several parts of the table may be made and substituted for those herein shown and described without departing from the nature and principle of my invention.

Having thus described my invention, what I claim and desire to secure by Letters Patent is—

1. For use with hospital charts and the like having a hinge pin with projecting ears, a chart rack comprising spaced parallel support bars having a plurality of recesses for retaining the projecting ears, said support bars being provided with bores at their upper and lower ends, each support bar being provided across its upper surface with two transversely extending parallel slots respectively opening downwardly into the upper and lower bores thereof, the bores in the upper ends of each support bar being axially aligned with each other and the bores in the lower ends of each support bar being likewise axially aligned with each other, shafts extending axially through said bores, driving spools mounted on said shafts and engaged bearingwise within each of said bores, said spools each being provided on its outer surface with a spiral groove, and a locking bar movably disposed on the upper surface of each support bar and being provided at its upper and lower ends with downwardly projecting members extending, respectively, through the upper and lower slots of said support bar for engagement within the grooves of said spools whereby on rotation of the shafts the locking bars are moved cross-wise with respect to the support bars into position to prevent unauthorized removal of the charts from the rack.

2. For use with hospital charts and the like having a hinge pin with projecting ears, a chart rack comprising spaced parallel support bars having a plurality of recesses for retaining the projecting ears, said support bars being provided with bores at their upper and lower ends, each support bar being provided across its upper surface with two transversely extending parallel slots respectively opening downwardly into the upper and lower bores thereof, the bores in the upper ends of each support bar being axially aligned with each other and the bores in the lower ends of each support bar being likewise axially aligned with each other, shafts extending axially through said bores, driving spools mounted on said shafts and engaged bearingwise within each of said bores, said spools each being provided on its outer surface with a spiral groove, a locking bar movably disposed on the upper surface of each support bar and being provided at its upper and lower ends with downwardly projecting members extending, respectively, through the upper and lower slots of said support bar for engagement within the grooves of said spools whereby on rotation of the shafts the locking bars are moved cross-wise with respect to the support bars into position to prevent unauthorized removal of the charts from the rack, and means for maintaining the locking bar in desired position.

3. A portable chart carrier comprising a housing having a bottom wall mounted on casters, front, side and rear walls marginally secured to the bottom wall and to each other, said rear wall being of substantially greater height than the front wall and said side walls having oblique upper margins connecting the upper margins of the front and rear walls in the provision of a housing with an obliquely presented top opening, chart holding bars mounted in and extending transversely across said opening parallel to the plane thereof, said bars each being provided with a uniformly spaced set of vertically aligned upwardly opening U-shaped slots, one slot in each set being horizontally aligned with a corresponding slot in each other set to provide opposed pairs of slots adapted to form stirrup-like supports for hospital charts, a flat elongated locking member slidably mounted on the upper face of each bar and confined for movement transversely with respect to the bar, said member being substantially narrower than the bar so that, when disposed in inwardly shifted position, it will leave all the slots uncovered but when in outwardly shifted position, will overlie the slots to prevent upward removal of charts therefrom and actuating means for simultaneously moving all locking members into and out of said overlying position.

4. For use with hospital charts and the like having a hinge pin with projecting ears, a chart rack comprising spaced parallel support bars having a plurality of recesses for retaining the projecting ears, said support bars being provided with bores at their upper and lower ends, each support bar being provided across its upper surface with two transversely extending parallel slots respectively opening downwardly into the upper and lower bores thereof, the bores in the upper ends of each support bar being axially aligned with each other and the bores in the lower ends of each support bar being likewise axially aligned with each other, shafts extending axially through said bores, driving spools mounted on said shafts and engaged bearingwise within each of said bores, said spools each being provided on its outer surface with a spiral groove, a locking bar movably disposed on the upper surface of each support bar and being provided at its upper and lower ends with downwardly projecting members extending, respectively, through the upper and lower slots of said support bar for engagement within the grooves of said spools whereby on rotation of the shafts the locking bars are moved cross-wise with respect to the support bars into position to prevent unauthorized removal of the charts from the rack, a gear pinned to each of said shafts, and rack means extending between said gears and engaged therewith for causing said shafts to move simultaneously.

HYMAN ROBERT SHAMPAINE.
